[57] **CLAIM**

The ornamental design for a horse gate, as shown.

DESCRIPTION

FIG. 1 is a perspective view of a horse gate showing our new design;

FIG. 2 is a front view thereof;

FIG. 3 is a top view thereof;

FIG. 4 is a bottom view thereof;

FIG. 5 is a rear view thereof;

FIG. 6 is a right side view thereof as viewed in FIG. 2; and,
 FIG. 7 is a left side thereof as viewed in FIG. 2.

The horse gate is broken in the center to indicate indeterminate length.
